UNITED STATES PATENT OFFICE.

ZENA ECKELBARGER, OF GOSHEN, INDIANA.

PHONOGRAPH.

Application filed March 17, 1924. Serial No. 699,700.

This invention relates to phonographs and particularly to the sound box therefor.

The principal object of the invention is to provide means for adjusting the vibrator 5 arm of the sound box of a phonograph, whereby the tone volume may be regulated, and whereby a softer tone, one free from metallic sounds, is produced.

The preferred embodiment of the invention is illustrated in the accompanying drawing in which Figure 1 is a side elevation of a sound box of a phonograph having my invention applied thereto; Fig. 2 illustrates two views, a side elevation and plan, of the 15 hub of the vibrator arm; and Fig. 3 is an enlarged fragmental view of a portion of the sound box in section and the vibrator arm adjustment means.

Similar numerals of reference indicate like parts throughout the several views on the drawing.

Referring to the details of the drawing the numeral 1 indicates a phonograph sound box provided with a depending fork 2 at its periphery, said fork being adapted to carry the vibrator arm 3, as hereinafter described. The inner end of the vibrator arm 3 extends to the center of the sound box 1 and engages the diaphragm—not shown—as is well known in the art. The outer end of the arm 3 is provided with the two hub sections 4 and 5 projecting in opposite directions and disposed between the two prongs of the fork 2. The arm hubs 4 and 5 are pivotally mounted upon the two pins 8—only one being shown—which may be screw-threaded through the prongs of the fork 2 axially of each other and engage in the recesses 6 and 7 formed coaxially in the ends of the hubs 4 and 5.

The numeral 9 indicates the hub of the two stylus arms 10 and 11 which are provided with the varied stylus needles or points 12 and 13, respectively, which are described and claimed in my copending application Serial Number 409,292, sound reproducing device, and which forms no part of

this invention. The hub 9 is rotatably mounted upon the shaft 14 which is suitably mounted in the socket 15 formed in the boss 50 16 of the hub of the arm 3 and coaxially therewith, Fig. 3.

The numeral 17 indicates an arm rigid with the hub of the arm 3 and projecting laterally therefrom through the opening 18 55 formed in the under side of the hollow casing 19 which is rigid with the box 1 and positioned above the fork 2. The casing 19 is tubular, as stated, the outer end whereof is adapted to be closed by the screw plug 20 60 adjustably mounted therein. The chamber or interior of the casing 19 is intersected intermediate its extremities by the lateral opening 18 to admit the arm 17 thereinto, and the balls 21 and 22, disposed within said 65 casing upon opposite sides of the arm 17, are caused to yieldingly engage said arm by the coil tension springs 23 and 24, respectively, also arranged within said casing. The spring 24 may be seated at the end wall of 70 the casing interior, and spring 23 is seated upon the adjustable plug 20, whereby tension of said springs may be regulated and adjustment of the arm 17 and vibrator arm 3 effected to regulate the tone volume and 75 quality and to eliminate the vibration of the parts of the device.

I claim:

In a device of the class described, the combination with a sound box provided with 80 a pivotally mounted vibrator arm, of a hollow casing carried by said sound box and provided with a lateral opening, an adjustment arm projecting laterally from said vibrator arm and extending through said casing opening to the casing interior, a spring 85 pressed ball engaging on each side of said arm and disposed within said casing, and means to adjust the tension of the springs 90 engaging said balls.

In witness whereof I have hereunto affixed my hand this 10th day of March, 1924.

ZENA ECKELBARGER.
